UNITED STATES PATENT OFFICE.

JOSIAH M. TRUESDELL, OF CHICAGO, ILLINOIS.

HEAT-CONSERVER.

1,367,333.

Specification of Letters Patent. Patented Feb. 1, 1921.

Application filed December 3, 1917. Serial No. 205,174.

To all whom it may concern:

Be it known that I, JOSIAH M. TRUESDELL, a citizen of the United States, residing at Chicago, in the county of Cook and State of Illinois, have invented certain new and useful Improvements in Heat-Conservers, of which the following is a specification.

The invention has for an object to effect improvements in devices used for conserving heat beneath receptacles over gas burners and the like, and aims particularly to simplify the manufacture and increase the efficiency of those devices in the form of rings adapted to be used upon stoves around the burner. It is an aim to present a device to receive the receptacle directly thereon by which the opening through the ring at the upper side is closed by the receptacle, and whereby the ring will conserve and focus upon the bottom of the receptacle, the heat passing upwardly from the burner. A further aim of the invention is to produce a device which is adapted for use with large and small receptacles without necessity for adjustment, and which will be efficient with both large and small receptacles.

Additional objects, advantages and features of invention may appear in the device, from the construction arrangement and combination of parts described hereinafter and shown in the drawings, wherein,

Figure 1 is a bottom view of the device constructed in accordance with my invention;

Fig. 2 is a cross section thereof,

There is illustrated a heat conserver for gas stoves formed of sheet metal, and comprising a cylindrical wall portion 10, having a lower edge portion turned inward to extend horizontally, forming a base flange 14, extending inwardly from the wall a distance of approximately one-eighth of an inch, as formed in practice. In practice number twenty-seven gage galvanized sheet iron has been used for the formation of the wall and flange 14.

A top flange 16 is provided, of frustoconical form, providing a central opening 17 considerably smaller than the diameter of the space within the wall 10. In practice, the wall 10 is made of a diameter of six inches, while the flange 16 is formed to extend inwardly from the wall one inch, thus making an opening in the neighborhood of four inches in diameter through the top of the device. The flange 16 is provided with

a series of circumferentially spaced tongues 21 cut and pressed from the body of the flange 16, being taken from material extending transversely of the flange from closely adjacent the outer edge to a point closely adjacent the inner edge of the flange, and being left attached at their outer ends. These tongues are utilized to hold in place a strip of asbestos 22, having a width corresponding to the height of the wall 10 between the flanges 14 and 16, between which it is adjusted lying close against the inner face of the wall 10, while the tongues 21 are lying in a plane with the body of the flange 16, and after proper adjustment of the asbestos, the tongues 21 are bent downwardly against the inner surface of the asbestos 22, holding it outwardly against the wall 10, so that it will be properly supported by the flange 14. In this way the necessity is obviated for extending the lower edge of the wall 10 so as to engage the inner side of the asbestos strip, and the formation of the support for the asbestos at the lower edge is greatly simplified. By my construction, I am able to form the tongues 21 of a length sufficient to hold the lower part of the asbestos securely in position to rest upon the flange 14, at the same time that the upper edge portions are held adjacent the bases of the tongues 21.

In order that when a large receptacle is disposed upon the device the flange portion will not ward heat away from the outer bottom portion of the receptacle, the device is so formed that the heat may act upon the receptacle over the flange. This may be accomplished in one or more ways, one method consisting in forming the flange 16 in the shape of the frustum of an inverted cone, so that its inner edge portions will extend downwardly away from the bottom of a large receptacle set thereon, leaving a space over the flange for access of heat to the bottom of the receptacle thereover. When a small receptacle is disposed upon the flange 16 as formed in this manner, it will be readily understood that the receptacle will be efficiently supported at its extreme edge portions where it rests upon the flange 16, while the inner portion of the flange will extend under the receptacle and slightly downward therefrom, permitting heat to circulate under the receptacle all the way to the point of contact with the flange 16, while the escape of heat outwardly of the recep-

tacle is prevented by the lower portion of the flange 16.

The provision of apertures in the top flange of the device as described results in 5 permitting the escape of a certain amount of gases tending to accumulate within the device when a receptacle is set thereover, in use, thereby preventing the retention of consumed gases from the flame for an un- 10 duly long period.

What is claimed:

A heat conserver of the character de- 15 scribed comprising a ring body having a cylindrical wall and an inturned horizontal flange at the lower part, and a top element for support of utensils constructed to rest

upon the cylindrical wall of the first named member and having a supporting portion projecting inwardly therefrom, tongue ele- 20 ments struck from said supporting portion and pressed downwardly to lie parallel to said cylindrical wall and in spaced relation thereto, and a cylindrical heat insulating member confined between said tongues and cylindrical wall.

In testimony whereof I have affixed my signature in presence of two witnesses.

JOSIAH M. TRUESDELL.
